TOBACCO FEEDING APPARATUS

Joseph W. Giles, Philadelphia, Pa., assignor to
J. W. Giles, Inc., Philadelphia, Pa., a corpora-
tion of Pennsylvania

Application November 11, 1936, Serial No. 110,249

15 Claims. (Cl. 131—39)

The object of this invention is to devise a novel and simplified apparatus for feeding measured quantities of scrap tobacco to a bunching machine.

5 Further objects of the invention are to devise novel means for raising tobacco from the bottom of its container and discharging it into a novel measuring device, novel means for actuating the measuring device, and novel means for moving 10 the charge of tobacco delivered from the measuring device into the pocket of the rolling apron of a cigar bunching machine.

With the above and other objects in view as 15 will hereinafter clearly appear, my invention comprehends a novel and simplified apparatus for feeding measured quantities of scrap tobacco.

Other novel features of construction and advantage will hereinafter appear in the detailed description and the appended claims.

20 For the purpose of illustrating the invention I have shown in the accompanying drawings a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

30 Figure 1 is a top plan view of a tobacco feeding apparatus embodying my invention.

Figure 2 is a side elevation.

Figure 3 is a side elevation similar to Figure 2 but partly broken away and showing certain of 35 the parts in a different position.

Figure 4 is a side elevation showing more particularly the measuring device, funnel, shutter and their adjuncts.

Figure 5 is a side elevation of the cam in a position 40 it assumes during the operation.

Figure 6 is a detail of a frame.

Figure 7 is a detail of a shutter operating means.

Figure 8 is a perspective view of a scoop.

45 Figure 9 is a perspective view, partly broken away, of the measuring device.

Similar numerals indicate corresponding parts.

Referring to the drawings:—

1 designates a tobacco container of circular 50 formation, and open at its top to receive the scrap tobacco.

The apparatus is driven in any desired manner, for example by an electric motor 2 having a sprocket wheel 3 around which passes a chain 55 4 which also passes around a sprocket wheel 5

to a shaft 6 suitably journalled in the container 1.

An arm 7 is fixed at one end to the shaft 6 and a scoop 8 is fixed to the offset free end of the shaft so that it travels in proximity to the inner wall of the container 1. During each revolution of the shaft 6, the scoop 8 removes a quantity of tobacco from the container. The arm 7 is made in sections. One section has slots 9, see Figure 3, and the other section has screws 10 which provide means to effect the longitudinal adjustment of the arm 7. The construction of the scoop 8 is best seen in Figure 8 from which it will be seen that the scoop has a rear member 11 from which an inner side member 12 flares forwardly, side flanges 13 and a bottom flange 14.

The tobacco is discharged from the scoop 8 into a novel chute 15 having spaced bottom plates 16 which form a slot 17 and adjustable side plates 18. The side walls are pivotally connected at 19 to the bottom plates, and at their forward ends are provided with brackets 20 which are fixed in their adjusted position by fastening devices 21 passing through slots 22 in the bottom plates. The bottom plates have arms 23 fixed to a rock shaft 24 journalled in the tobacco container. This rock shaft is rocked by an arm 25 fixed thereto and pivotally connected with a link 26 pivotally connected to a lever 27 fulcrumed at 28 and having a roller 29 which cooperates with a cam 30 on the shaft 6.

The tobacco discharges from the chute into a measuring device 31 in the form of a bucket having a bottom wall, side walls, end walls and an open top. This bucket is fixed in any desired manner to a rock shaft 32. An arm 33 is pivotally connected with a link 34 pivotally connected to a lever 35, fulcrumed at 36 on the container 1 and having a roller 37. This roller 37 travels in a cam groove 38 of a cam 39 fixed on the shaft 6. A spring 40 has one end connected 40 to the pivotal connection of the link 34 and the lever 35, and its opposite end is connected to a fixed point on the apparatus, see Figure 4. A cam member 41, see Figures 1 and 4, is fixed to the rock shaft 32 and has a cam face 42 cooperating with a roller 43 on an arm 44 fixed to a rock shaft 45 which also carries a baffle 46 which has its movement in an outward direction limited by a stop rod 47. The bucket 31 is between side plates 48, which contribute to form a funnel, the bottom of which is closed by an inclined shutter 49. The upper end of the shutter normally rests against a stop 50, and its lower end portion is fixed to a rock shaft 51. An arm 52 fixed to the rock shaft 51 has one end of a spring 53 con- 55

nected to it, the other end of such spring being secured to a fixed point of the apparatus.

The front of the funnel is formed by a reciprocatory frame 54 having rollers 55 travelling in 5 guide slots 56 in side frame members 57, see Figure 1. A link 58 is connected with the frame and with a lever 59 fulcrumed at 60 and having a roller 61 which travels in the cam groove 38 of the cam 39.

10 The gate 54 has fixed to it a bar 62, by fastening devices 63 passing through a slot 64 in a side member of the fixed frame. The bar 62 is positioned so that during the downward movement of the reciprocatory frame 54 it contacts a roller 65 15 on an arm 66 fixed to the rock shaft 51 to cause the shutter 49 to move from the position seen in Figure 2 to that seen in Figure 3.

A plunger 67 is provided to press the tobacco into the pocket of the apron of the rolling or 20 bunch forming machine.

The plunger 67 is connected by a longitudinally adjustable link 68 with a lever 69 fulcrumed at 70 and provided with a roller 71 which travels in the cam groove 38 of the cam 39. A lever 72 25 controlled by the cam 30 controls in the conventional manner the apron of the rolling or bunch forming mechanism 73.

The operation of my novel tobacco feeding apparatus will now be apparent to those skilled 30 in this art and is as follows:

Assuming now that the scrap tobacco has been placed in the tobacco container 1 and the motor started, the shaft 6 will be revolved in the direction of the arrow seen in Figure 2 thereby causing 35 the scoop 8 carried by its arm 7 to pass into the container as shown in Figure 3 in proximity to the bottom of the container and remove a quantity of tobacco and discharge it into the chute 15, and therefrom into the measuring device 31. The arm 7 of the scoop 8 passes through the slot 17 in the chute 15, and the chute is rocked from the position seen in Figure 2 to that seen in Figure 3 to permit the scoop 8 to pass beyond it. This is caused by the roller 29 of cam lever 28 40 passing down the cam face 74 to the dwell portion 75.

The roller 29 next engages the cam face 76 to return the chute to the position seen in Figure 2, in which it is retained by the face 77 of the cam 30.

50 The charge of tobacco is now in the measuring device or bucket 31.

The inner wall of the cam groove 38 of the cam 39 has a depression 78 so that when the cam 39 reaches the position seen in Figure 5 the roller 37 55 will pass into such depression and through its cam lever 35, the link 34 and cam 33 rocks the rock shaft 32 and thereby imparts a shaking movement to the measuring device 31 to effect the removal of any excess tobacco contained 60 therein.

The next operation is to discharge the measured charge of tobacco from the measuring device 31 into the funnel.

65 The cam 39 now moves into the position seen in Figure 4 causing the cam lever 35, link 34 and cam 35 to rock the rock shaft 32 to which the measuring device 31 is fixed discharging the measured charge of tobacco into the funnel where 70 it rests on the shutter 49. As the roller 43 leaves the cam face 42 the arm 44, rock shaft 45 and baffle 46 moves from the position seen in Figure 3 to that seen in Figure 4, the baffle resting against the stop rod 47.

75 The roller 61 of cam lever 59 now reaches

the high point of the cam groove 38 causing the frame 54 to move downwardly. This frame 54 includes a plate 81 which closes the front end of the funnel. The bar 62 on the frame 54 engaging the roller 65 rocks the arm 66 and rock shaft 51 thereby moving the shutter 49 from the position seen in Figure 2 into that seen in Figure 3 and the measured charge of tobacco for making a bunch of the predetermined size is discharged 10 into the pocket of the rolling apron.

10 The plunger 67 now moves downwardly to press the tobacco into the pocket of the apron. This is effected by the cam 39 rocking the lever 69 and causing the link 68 to move downwardly 15 the plunger 67.

15 As the cam 39 revolves the shutter 49 is returned to its normal position and the measuring device 31 is returned to its receiving position, and the cycle of the operation is repeated.

The cam 41 returns to its initial position and 20 the roller 43 engaging the cam returns the baffle 46 to its initial position seen in Figure 3. The roller 43 cooperates with the cam face 42 to retain the measuring device 31 stationary when in position to receive tobacco from the chute 15. 25

In accordance with this invention, I eliminate the necessity of employing a knife to cut off the surplus tobacco and also the formation of a hard bunch.

30 The tobacco in the measuring device is not subjected to pressure and a loose fluffy bunch is formed which provides for a free smoking cigar.

The measuring device may have an adjustable false bottom 79 which can be raised or lowered by a screw 80 and which may have any desired 35 contour depending on the shape of the finished cigar. In Figure 9 I have shown this bottom curved so that the bunch will be thicker at its central portion than it is at its end portions.

40 It will now be apparent that I have devised a new and useful tobacco feeding apparatus which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention 45 or sacrificing any of its advantages.

Having thus described my invention, what I claim as new and desire to secure by Letters Patent is:

1. In a tobacco feeding apparatus, a tobacco 55 container, means to scoop tobacco from said container, a chute receiving tobacco from said means, a tobacco measuring device pivotally supported and into which tobacco is discharged from said chute, a cam on said container, means cooperating with said cam to agitate said measuring device to cause it to contain a predetermined charge, and means to actuate said measuring device to empty it.

2. In a tobacco feeding apparatus, a tobacco 65 container, means to scoop tobacco from said container, a chute receiving tobacco from said means, a tobacco measuring device into which tobacco is discharged from said chute, means to agitate said measuring device to cause it to contain a predetermined charge, a cam on said container, means cooperating with said cam to actuate said measuring device to empty it, a funnel to receive the charge from said device and having a movable bottom, a member clos- 70 75 80 85 90 95 98

ing the front end of said funnel, means to move said bottom to form a charge receiving space between it and said member, and means to move the measured charge from said space.

5 3. In a tobacco feeding apparatus, a measuring device, means to feed tobacco thereto, means to impart a shaping movement to said measuring device while in its tobacco receiving position to remove excess tobacco over a predetermined charge, and means to deliver said charge to a desired point of utilization.

10 4. In a tobacco feeding apparatus, a rockable measuring device, means to feed tobacco thereto, means to impart a shaking movement to said device while in its tobacco receiving position to remove excess tobacco and to thereafter rock said device to discharge tobacco therefrom, and means to retain said device in its tobacco receiving position.

20 5. In a tobacco feeding apparatus, a rock shaft, a measuring device fixed thereto, a cam on said shaft, means cooperating with said cam to normally hold said device stationary, and a cam controlling the rocking of said shaft and having 25 a cam face to rock said shaft to agitate said device to remove excess tobacco prior to discharge of tobacco therefrom.

6. In a tobacco feeding apparatus, a rock shaft, a measuring bucket fixed thereto, a cam on said 30 shaft, a pivoted deflector, means connected therewith and cooperating with said cam to hold said device stationary, means to rock said shaft to agitate said device to remove excess tobacco therefrom, and to thereafter effect the delivery 35 of a measured charge from said measuring device.

7. In a tobacco feeding apparatus, a measuring 40 bucket pivotally supported, a funnel having a pivoted shutter at its bottom, a reciprocatory frame in front of said shutter, means to empty said bucket into said funnel, means to reciprocate said frame, means on said shutter in the path of the downward movement of the frame and contacted by the frame to move said shutter to form with the frame a delivery space, and 45 plunger means movable in said space to feed the tobacco therefrom.

8. In a tobacco feeding apparatus, a tobacco 50 container, means to scoop tobacco therefrom, a chute through which said means passes, means to move said chute to permit the passage of said means, a measuring device receiving tobacco from said chute, means to actuate said device to

cause it to retain a determined charge, and means to deliver said charge in a loose, fluffy, condition to a bunching machine.

9. In a tobacco feeding apparatus, a container, a scoop having substantially the shape of a dust 5 pan with the open side of the pan presented to the periphery of the container, means to revolve said scoop in said container to remove tobacco therefrom in a loose, fluffy, condition.

10. In a tobacco feeding apparatus, a container, 10 a driven shaft mounted therein, a scoop actuated by said shaft, a pivoted chute having a slot there-through and receiving tobacco from said scoop, a cam on said shaft operatively connected with said chute to actuate it, and means to measure 15 the tobacco passing from said chute into predetermined uniform charges, each of the proper amount to form a bunch of predetermined size.

11. In a tobacco feeding apparatus, a tobacco 20 container of circular formation and open at its top, a driven shaft, an arm thereon longitudinally adjustable, a pan shaped scoop on said arm, a sectional chute through which said arm passes, and cam means on said shaft to rock said chute to permit the scoop to pass by it. 25

12. In a tobacco feeding apparatus, a tobacco 30 container, a scoop to travel through said container and having an outer wall and an inner wall, the outer wall being of less depth than the inner wall, and means to actuate said scoop. 30

13. In a tobacco feeding apparatus, a container, a scoop within the container, an arm carrying said scoop, a chute having a slot to permit said arm to pass through it, means to revolve said arm, in the container, and means to rock 35 said chute to permit said scoop to pass between it and the container.

14. In a tobacco feeding apparatus, a rock 40 shaft, a measuring bucket carried by said rock shaft, a cam fixed to said rock shaft and provided with a cam face, a baffle above the bucket controlled by said cam face, and cam means to turn said shaft and during such turning impart to it a shaking movement to remove excess tobacco from the bucket. 45

15. In a tobacco feeding apparatus, a rock 50 shaft, a measuring bucket fixed to said shaft, cam means, and means to turn said shaft to move the bucket into discharging position and to shake the shaft during the first part of its turning movement to remove excess tobacco from the bucket. 50

JOSEPH W. GILES.
